UNITED STATES PATENT OFFICE

2,008,774

ROTARY MACHINE

John D. Spalding, Los Angeles, Calif., assignor,
by mesne assignments, to The National Superior Company, Toledo, Ohio, a corporation of Delaware

Application July 21, 1933, Serial No. 681,518

36 Claims. (Cl. 255—23)

This invention relates to rotary machines and more particularly to a rotary machine of the fully enclosed type and to improvements therein applicable to either the "make and break" type of rotary, as disclosed in Letters Patent No. 1,596,569 and No. 1,782,769, issued to Lewis E. Zerbe and John D. Spalding, respectively, and which may likewise be incorporated in the conventional type of rotary machine as disclosed in the co-pending application of David S. Faulkner, et al., Serial No. 504,758, filed December 26, 1930. As applied to either the "make and break" type or conventional type of rotary machine, this invention relates to an improvement in the base and table structure of such a rotary machine so as to fully enclose in a unitary housing the gears, bearings and operative parts of the rotary machine.

An object of this invention is to provide a fully enclosed rotary machine with a bearing structure for the rotary gear table, including a main or supporting bearing and an upthrust bearing assembled with the gear table to provide a unitary or self-contained unit which can be positioned within and removed from the rotary table as a unit and without disturbing the initial bearing adjustment.

Another object of this invention is to provide a rotary machine in which provision is made for the supplying of independent lubricant to the gear table bearing, the table gear and pinion and the pinion shaft bearing from separate openings conveniently grouped for servicing by the operator of the rotary machine.

Another object of this invention is to provide a rotary machine with an outwardly extending portion to house the pinion shaft unit, said extending portion having a flat, box-like top upon which pipe might be racked, and which likewise provides an improved and safe footing for the operators working around the machine.

Another object of this invention is to provide an improved type of rotary machine of such construction that the base is applicable for supporting the heavy loads, particularly such as are incident to the operation of the "make and break" type of rotary machine wherein the pipe or casing is suspended from a spider or bushing supported on the base structure.

Another object of this invention is to provide an improved rotary machine in which there is provided an improved form of mud deflector mounted around the rotary table to provide protection against water or mud entering the table enclosure, and also to prevent the mud being

thrown centrifugally onto the operators from the surface of the gear table when rotating.

Another object of this invention is to provide a rotary table in which there is provided a gear and pinion lubricant reservoir, and in which means are provided to limit the level to which the lubricant may be filled in said reservoir, and also to vent from the bottom of the reservoir the used or old lubricant or water upon the introduction of new lubricant into the reservoir.

Another object of this invention is to provide a rotary machine in which there is provided a means for forcibly draining the lubricant from the reservoir without the necessity of removing a drain plug or other mechanism.

Other objects and advantages of this invention it is believed will be apparent from the following detailed description of a preferred embodiment thereof as illustrated in the accompanying drawings.

In the drawings:

Figure 1 is a side elevation of a rotary machine embodying my invention.

Figure 2 is a sectional side elevation thereof.

Figure 3 is a top plan view of the rotary machine partly in horizontal section and with the gear table assembly removed from the base.

Figure 4 is a sectional end elevation taken substantially on the line 4—4 of Figure 3 showing the rotary gear table in position with the spider in "make-up" position.

Figure 5 is a sectional end elevation of the base of the rotary machine taken substantially on the line 5—5 of Figure 3.

Figure 6 is a sectional end elevation through 35 the pinion shaft portion of a rotary machine taken substantially on the line 6—6 of Figure 2.

Figure 7 is a top plan view partly in section of the rotary or gear table showing the spider in cross section taken substantially on the line 7—7 40 of Figure 2.

Figure 8 is a top perspective view of the rotary machine embodying my invention with the table guard removed.

Figure 9 is a perspective view of the rotary machine base embodying my invention looking upwardly from the under side thereof.

Figure 10 is a fragmental sectional view taken substantially on the line 10—10 of Figure 8.

Figure 11 is a fragmental sectional view similar to Figure 10 in a modified form of the structure embodying my invention.

Figure 12 is a fragmental sectional view similar to Figure 10 of a further modified form of structure embodying my invention.

Figure 13 is a diagrammatic plan view of the mud, water or other foreign substances, the table 7 or the ring gear 8 of the table 7 is formed with a groove 13 which cooperates with the upper end of the annular wall 2 the edge of which fits within the groove 13 to form an enclosure within the base 1.

5 Figure 14 is a sectional view taken substantially on the line 14—14 of Figure 13 of a rotary machine embodying my invention of the conventional type and showing the lock pawls removed.

10 Figure 15 is an end sectional view taken substantially on the line 15—15 of Figure 14 illustrating the base casting with the table and pinion assemblies removed.

15 In the preferred embodiment of my invention as illustrated in the accompanying drawings, 1 indicates the base of a rotary machine and which includes an upstanding annular wall 2 and an outwardly extending pinion shaft portion 3 which is preferably formed integral with the base 1 to provide a housing 4 for a unitary pinion shaft assembly 5 preferably in the manner as disclosed in the copending application of Lewis E. Zerbe, Serial No. 655,212, filed February 4, 1933.

20 The outwardly extending portion 3 of the base 1 is preferably so formed as to provide a box-like structure having a flat upper surface 6 giving to the entire rotary machine base a deep, box-like appearance. The construction of the base in this manner provides a platform upon which pipe may be racked, and likewise provides a platform 25 for the operators of the rotary machine enabling the operators to more readily grip the slips, bushings or other objects which may be utilized in connection with the rotary drilling process.

25 Mounted within the opening formed through the base 1 of the rotary machine is a rotary or gear table 7 which is housed, except for its upper surface, within the annular wall 2 of the base 1. The upper surface 18 of the rotary table 7 is preferably in substantially the same plane with the upper surface 6 of the outwardly extending portion 3 of the base 1, as is more clearly shown in the perspective view of Figure 8. The rotary table 7 is formed with a downwardly extending sleeve or skirt 7^a which extends downwardly into 30 the base 1 of the rotary machine within the annular wall 2.

35 The rotary table 7 is preferably formed so as to carry the supporting bearing 9 and the upthrust bearing 14 upon which the rotary machine is supported and held from vertical displacement respectively within the base 1 of the rotary machine. The rotary table 7 and the bearing assemblies 9 and 14 are thus carried by the table 1 as a unit so that the initial adjustment of the bearings may be provided when the rotary table 40 is removed from the base and is so carried that the adjustment thus provided will not be disturbed upon the insertion of the unit consisting of these bearings and the table into the base of the rotary machine.

45 In order to drive the rotary table with respect to the base, the rotary table is provided with a ring gear 8 which is adapted to mesh with a pinion 12 carried by the shaft 33 of the unitary pinion shaft assembly 5.

50 In order to permit insertion of the unitary pinion shaft assembly 5 into the housing 4 so that the pinion 12 will mesh with the ring gear 8, an opening 11 is formed in the upstanding wall 2 within the enclosure formed by the housing 4 of the outwardly extending pinion shaft portion 3 of the base 1.

55 In order to form an enclosure within the base 1 to protect the gears and bearings of the rotary machine from foreign matter such as the rotary

60 5 groove 13 which cooperates with the upper end of the annular wall 2 the edge of which fits within the groove 13 to form an enclosure within the base 1.

65 In order to provide the unitary assembly of the rotary table 7 and the supporting bearing 9 and upthrust bearing 14, I prefer to provide the following construction which includes a thrust ring 16 which is mounted upon a shoulder 17 formed within the base 1. The thrust ring 16 is removably secured to the base 1 by means of a plurality of bolts 18 which are passed through holes 19 formed in the base 1 and are threaded to the ring 16. Access is had to the bolts 18 through openings 21 provided in the longitudinally extending sill or skid portions 20 of the base 1.

70 10 In order to locate the ring 16 within the rotary machine before it is secured in position by the bolts 18, a plurality of dowels 22 which register with corresponding dowel holes formed in the rings 16 are provided to correctly orient the ring 16 within the base of the rotary machine.

75 15 If desired, a thin sheet gasket may be employed between the mating faces of the ring 16 and the shoulder 17 of the base 1 to seal off this joint against all leakage.

80 20 The thrust ring 16 is formed to provide a channel in which the race ring 16^a of the supporting bearing 9 is fitted. Bearing members are mounted between the race rings 16^a and a second race ring 16^b which is operatively engaged with the skirt 7^a of the rotary table 7.

85 25 The channel formed in the thrust ring 16 provides a means for maintaining lubricant around the bearing 9 and the outer wall 16^c of the thrust ring 16 is extended upwardly to overlap a downwardly depending flange 15 formed on the under portion of the table 7 to prevent the inter-change 30 of lubricant between the bearing 9 and the pinion 12 and the ring gear 8.

90 35 The upthrust bearing 14, including the race rings 14^a and 14^b and the bearing member are mounted upon a retaining ring 19 which is threaded to the lower end of the skirt 7^a of the rotary machine 1.

95 40 The retaining ring 19 is adjustably secured to the skirt 7^a so as to enable an initial adjustment of the positions of the supporting and upthrust bearings 9, which adjustment is locked by means of a locking dowel 23 which is passed through an opening formed in the retaining ring 19 and into a corresponding opening from the lower part of the skirt 7^a and held in position by means of a plug 24. The upper race ring 14^a of the upthrust bearing fits within a groove 25 formed in the lower portion of the thrust ring 16 to maintain a unitary form of construction so that all of the parts in the unitary structure are carried by the table 1 of the rotary machine and may be withdrawn from the rotary base or placed in the rotary base without disturbing the setting of the bearings 9 and 14.

100 45 In order to retain lubricant around the upthrust bearing 14, and likewise to prevent the introduction of foreign matter into this bearing assembly, the supporting ring 19 is formed with an upwardly extending flange 26 which closely fits within the interior of the bowl portion 27 of the base 1. The flange 26 on its interior provides a channel around the bearing 14 in which lubricant is maintained.

105 50 The unitary pinion shaft assembly 5, including the pinion shaft 33 and the spaced bearings 75

28 and 29 and the lock ring 30, are mounted with-in a housing sleeve 31 within the housing 4 pro-
vided by the outwardly extending portion 3 of the
base 1. A cap 32 is provided for the sleeve 31
5 on the interior of the housing 4 and is secured in
position to the end of the sleeve 31 by means of
cap screws 34. Interposed between the mating
faces of the cap 32 and the sleeve 31 are shims 35
10 to provide for the necessary adjustment of the
bearings.

In order to seal the shaft 33 where it projects
through the cap 32 is a packing groove 36 formed
on the inner periphery of the cap 32 to hold pack-
15 ing around the shaft 33. The shaft 33 is adapted
to be driven by an overhanging reversible
sprocket 37 which is reversibly keyed by means
of a key 38 to the overhanging or projecting por-
tion of the shaft 33.

The pinion 12 is keyed by means of a key 39 to
20 the inner end of the shaft 33. Mounted between
bearings 28 and 29 is a lock ring 40 provided with
radially projecting lock lugs through the medium
of which the shaft 33 of the unitary pinion shaft
25 assembly may be locked against rotation in either
direction by means of lock pawls 41 and 42 which
are enclosed within the outwardly extending portion
3 of the base 1 and are adapted to be actuated
20 by actuating levers 43 and 44 mounted upon
the actuating shafts of the lock pawls 41 and 42
30 at its end which projects from the housing 4
of the outwardly extending portion 3 of the base
1 in a manner substantially as disclosed in the co-
pending application of Lewis E. Zerbe, Serial No.
655,212, filed February 4, 1933.

35 The base 1 and the table 7 of the rotary ma-
chine are so formed as to provide three inde-
pendent and separate lubricant chambers or res-
ervoirs which include the lubricant reservoir 45
40 formed within the sleeve 31 of the unitary pinion
shaft assembly 5 in which lubricant is maintained
for lubricating the bearings 28 and 29; lubricat-
ing chamber 46 formed within the base of the
45 rotary table and maintained separated from the
lubricating chamber 45 by means of the cover
47 at one end which closes the hole 11 formed
50 through the annular rim 2, the downwardly pro-
jecting flange 15 of the rotary table 7 which co-
operates with the thrust ring 16, and the up-
standing wall forming the bowl 27 of the base 1
55 to close the reservoir 46 at its other end. Gear
lubricant is preferably mounted in the reservoir
46 to lubricate the meshing drive pinion 12 and
ring gear 8 of the rotary table.

The chambers 45 and 46 are sealed against
55 transfer of lubricant so that the proper lubri-
cation may be provided for each of the operating
assemblies. The third lubricating chamber is
provided within the base 1 of the rotary table
and exterior to the skirt 7^a of the rotary table 7
60 and is the lubricant chamber or reservoir 47
within which the bearings 9 and 14 are mounted.
This lubricant reservoir is sealed against trans-
fer of lubricant to or from the lubricant reservoir
47 by means of the overlapping flange 15 and
65 thrust ring 16 and the structure of the base 1
forming the bowl 27 and the structure of the
skirt 7^a of the table 7 which prevents admission
of foreign matter to within the chamber 47 from
70 within the interior of the rotary machine.

The chamber 47 is provided with bearing lubri-
cant particularly applicable for proper lubri-
cation of the bearings 9 and 14.

In order to supply lubricant to the three lubri-
75 cant reservoirs 45, 46 and 47, from a single con-

venient point I prefer to provide the following
construction:

Grouped at the end of the base 1 are three
lubricant inlets 48, 49 and 50 which are grouped
5 together to provide for the convenient lubrication
of all parts of the rotary machine. The lubricant
inlet 48 provides the inlet for the lubricant re-
quired for the reservoir 45. The lubricant inlet
49 provides the inlet through which the lubricant
is supplied for transferring the lubricant to the 10
reservoir 46. The lubricant inlet 50 provides the
inlet for the lubricant required for lubricating
the bearings 9 and 14 in the lubricant reservoir
15 47. Lubricant admitted to the inlet 48 flows
through a cored channel 51 formed in the struc-
ture of the base 1, passes through the cored chan-
nel 51 into a similar cored channel 52 formed
in the outwardly extending portion 3 of the base
1 through an inlet 53, and into the reservoir 45.
The channel 51 is separated from other channels 20
formed in the rotary base by means of separating
walls 54 and 55. The lubricant admitted into the
inlet 49 flows through a separately cored channel
56 around the opposite side of the structure of
25 the base 1 to deliver the lubricant into the lubri-
cant reservoir 46. A sediment trap 57 is formed
in the base structure to permit precipitation of
foreign matter which may be suspended in the
lubricant.

Lubricant is picked up by the pinion 12 and 30
carried upwardly to the gear 8 from which it is
thrown off and drained back to the reservoir 46.
A drain plug 58 permits draining of the lubri-
cating reservoir 46. A drain plug 59 in the side wall of the base permits drain-
ing the trap 57.

In order to maintain a fixed oil level in the
reservoir 46, there is provided an overflow outlet
60. A port 61 connects the overflow outlet with
the bottom of the reservoir 46. Upon any new 40
lubricant being added to the supply in the reser-
voir 46, the old lubricant which may be contami-
nated with water or other foreign matter in sus-
pension is displaced out through the port 61 and
outlet 60 draining through the bottom of the base 45
structure 1. In the event that water or slush
mud should enter the gear and pinion enclosure
and mix with the lubricant in the reservoir 46,
the overflow outlet 60 limits the level to which
50 the mixture can rise, and ordinarily if the rotary
machine is shut down for any time, the water
will precipitate to the lower portion of the reser-
voir 46 and will be displaced upwardly through
the port 61 and outlet 60 upon any new supply
of lubricant being added.

An ejector fitting 62 may be provided in the
reservoir 46 in order to eject the contents there-
from outwardly through the port 61 and outlet
60 upon steam or air being supplied through the
60 connecting conduits 63. The plug 64 for the con-
duit outlet 63 is positioned above the overflow
level of the outlet 60 and closes the opening to
the conduit 63. The passage forming the outlet
60 and the outlet port 61 is proportioned to co-
operate with the fitting 62 to obtain an effective
65 ejector and deflect the fluid downwardly upon
its being discharged from the outlet 60.

The inlet 50 provides the inlet for the lubricant
for the reservoir 47 and the inlet 59 is connected
with the reservoir or chamber 47 within which
70 the bearings 9 and 14 are mounted by means of a
cored passage 65 formed in the structure of the
base 1 and communicating by means of an open-
ing 66 with the chamber 47. The passage 65 is
provided with the depressed portion 67 in which 75

the lubricant may settle to settle out any foreign matter and the depressed portion 67 is provided with a drain plug 68 permitting draining of the lubricant from the passage 65. An inspection plug 69 is provided in the bowl 27 to permit inspection of the clamp bolts on the up-thrust adjusting ring.

In order to insure against the admission of rotary mud, water or other foreign matter into the interior of the rotary machine into either the lubricant reservoirs 46 or 47, the flat tressed portion 6 of the outwardly extending pinion portion 3 of the base 1 extends up to the periphery of the rotary table 7 and forms an upwardly projecting circular rib 70 which extends across the width of the base 1 and forms the outer wall of a circular groove 71. A labyrinth passage produced between the base 1 and the table 7 by the grooves 13 and 71 protects the gear table enclosure against the entrance of mud, water or other foreign matter. The bottom of the groove 71 slopes gradually from the center portion of the base to form openings 72 on the opposite faces of the rotary base 1. Any mud or water flowing over the table 7 drains into the groove 71 and hence outwardly through the openings 72. To increase the overflow capacity in the groove 71 there is provided in the wall which forms the bottom of the groove 71 a plurality of holes 73 that open directly on the under side of the base 1. If desired, semi-circular notches 74 can be formed in the upper rim of the rib 70 in alignment with the holes 73 to facilitate cleaning the latter with steam or water jet if desired.

To increase the effectiveness of the seal between the gear table 7 and the base 1, means may be provided as illustrated by Figures 11 and 12 to form a grease seal or a seal of other suitable substance which is illustrated in the modification 40 illustrated by Figure 11 and may be fed to the side walls of the grooves 71' through a suitable grease connection 72' which communicates with a lateral passage 73' in the table 7' or gear ring 8' thereof. The table 7' may be slowly rotated as grease is fed under pressure through the connection 72' so as to completely fill the clearance space which forms the labyrinth restriction between the table and the base.

In the modification illustrated in Figure 12 of the grease seal where the groove 71'' is not provided with a bottom drain, the connection 72'' communicates with a downwardly directed passage 73'' to supply grease to the bottom of the groove 71'', from which point it is forced upwardly to coat the side walls of the groove 71''. The entire bottom of the groove 71'' may be covered with grease by rotating the table 7'' as grease is fed under pressure through fitting 72''.

The top of the rotary table 7 is provided with a guard or mud deflector 75 as illustrated specifically in Figures 1, 2, 4 and 6. The mud deflector 75 consists of two halves which are secured to the lugs 76 of the base 1 by means of cap screws 77. The outer portion 78 of the guard 75 serves as a foot rest or circular platform around the rotary table and permits the operator to stand close to the drill pipe and handle the gripping slips which support the drill pipe in the opening through the table. The outer portion 78 of the guard 75 is also a mud deflector for deflecting the mud thrown centrifugally from the table top when the rotary is running. The inner portion 79 of the guard 75 has an inwardly projecting flange 80 which projects into an annular groove 81 in the table gear ring 8 to form an additional labyrinth

restriction against the entrance of foreign matter into the enclosure. The downwardly projecting flange of the portion 79 defines passages 82 and 83 for the drainage of mud or water thrown from the table 7.

The "make and break" rotary as illustrated in the preferred embodiment of my invention is preferably formed so that in the bore of the table 1 there is provided a set of diametrically opposed and spaced pockets 84 which are formed in inwardly projecting segmental lugs 85 and project into the bore of the gear table 7.

The lugs 85 are spaced apart so as to provide passages 86 between the lugs 85 so that the lugs 87 formed on the spider or bushing 88 may pass through the passages 86 to be supported within the pockets 89 formed in the integral supporting ring 90 of the table base 1. With the construction thus described the lugs 87 formed on the spider 88 are adapted to engage and to be supported by either the pockets 84 in the gear table 7 or in the pockets 89 of the base 1 solely by vertical movement of the spider 88 and rotation thereof to align the lugs 87 with the respective pockets.

Spider 88 is provided with a tapered bore 91 and a square-shaped recess 92 within which there is fitted the split table bushing 93. The bore of the bushing 93 is adapted to handle either the slips for supporting the drill pipe or the drill stem bushing for handling the drill stem in a manner well understood by those skilled in the practice of the well drilling art. When the bushing or spider 88 is supported in the pockets 84 of the table 7, the weight of the drill pipe or casing supported by the bushing is carried directly by the table 7 to the main bearing 9 which is supported by the shoulder 17 of the base 1.

When bushing 88 is supported in the pockets 89 of the base 1, the entire drill pipe load is then carried directly by the integral ring portion 90 of the base 1. In order to adequately support the ring portion 90, there is provided cross sills 94 which are flush with the longitudinal sill surfaces of the sills 20. The cross sills 94 are channels shaped in cross-section and merge into the annular bowl portion 27 of the base 1. Longitudinal and transverse webs 95 and 96 serve to reinforce and distribute the stresses in the base casting 1. Strut ribs 97 reinforce the channel shaped cross sills 94 and transverse webs 98 serve to tie the ring 90 into the base structure between the cross sills 94. Any slush or mud collected in the bowl 27 of the base 1 is drained through openings 99. When extremely heavy loads are to be encountered, such as when wells are being drilled to extreme depths, it may be desirable to frame the rotary drill support in the derrick so that the rotary base is supported longitudinally under the sills 20 and likewise transversely under the cross sills 94.

In the modification of my invention as illustrated in Figures 14 and 15, my invention is illustrated as adapted to a conventional type of rotary machine, that is, a rotary machine that is not of the "make and break" type.

In this modification of my invention, 101 illustrates the base of the rotary machine which has an inner upstanding wall 102 and an outer upstanding wall 103 surrounding the gear table 104 mounted on the bearings 105 and held in position by the bearings 106 within the base 101. The table assembly, including the table 104, bearings 105 and 106, is removable as a unit with the bearing thrust ring 107 in the same manner as hereto-

fore described in connection with the "make and break" type rotary.

The upthrust ring 107 is formed with a downwardly extending flange portion 108 which co-
5 operates with a complementary upstanding flange 109 of the base 101 to form an effective oil seal for the bearing 106. The oil or lubricant which overflows from the oil reservoir for the bearing 106 drains downwardly and forms a seal between 10 the flanges 108 and 109. The outwardly extending portion 110 of the base 101 provides a housing for the bearing housing sleeve assembly 111 within which is rotatably mounted pinion shaft 112.

15 The portion 113 of the base which supports the pinion end of the bearing housing sleeve is substantially cylindrical in cross section as illustrated in Figure 15 and forms a bridge between the inner and outer upstanding walls 102 and 103 re-
spectively.

Reinforcing webs 114 form an integral tie between the table portion and pinion shaft portion of the base 101. Radial webs 115 between the inner and outer walls 102 and 103 support 25 the inner portion of the base which forms the oil enclosure for the gear table 104. The construction as thus described provides a more effective enclosure for the gear table and bearings. Any mud that passes the rim of the outer wall 30 103 is deflected downwardly and drains through the bottom of the base 101.

To facilitate drainage of water that may be deflected upwardly from the surface of the outwardly extending portion of the base and pass 35 over the rim of the outer wall 103, there is provided a passage 116 formed between the inner wall 103 and the transverse wall 117.

The cylindrical bridge 113 and webs 114 are the only restrictions formed in the passage 116.

40 In the construction shown in Figures 14 and 15, it will be observed that all fluid which passes over the rim of the outer wall 103 is drained through the side of the rotary base into the cellar of the derrick. In other respects, except 45 that the modification illustrated in Figures 14 and 15 is of the conventional type rather than the "make and break" type rotary, the construction does not differ materially from that described in connection with the "make and break" 50 type rotary.

Having fully described my invention, it is to be understood that I do not wish to be limited to the details herein set forth, but my invention is of the full scope of the appended claims.

55 I claim:

1. In a rotary machine for drilling wells, the combination of a base, a gear table, a bearing for rotatably supporting the gear table with relation to the base, an upthrust bearing between 60 the base and the table, a bearing thrust ring supported upon a shoulder formed within the enclosure of the base, means for detachably securing the thrust ring to the base, one thrust race ring of each of said bearings being engaged with the bearing thrust ring, the other race ring of the upthrust bearing being carried by the gear table, the other thrust race ring of the supporting bearing being operatively engaged with the gear table so that upon release of the detachable se-
65 curing means for the thrust ring the gear table, including the supporting and upthrust bearing assemblies, may be withdrawn from the base as a unit.

70 2. In a rotary machine for drilling wells, the combination of a base having an upstanding an-

nular wall, a gear table mounted within the an-
nular wall, said table including a downwardly extending annular member, means providing an annular supporting shoulder within the enclosure of the base, a bearing thrust ring mounted upon the shoulder, a supporting bearing mounted upon the thrust ring to rotatably support the table, an upthrust bearing assembly operatively engaging the thrust ring, means for adjustably securing an element of the upthrust bearing assembly to 10 the downwardly extending annular element of the table to enable relative adjustment of the upthrust and supporting bearings between the table and the thrust ring, and means for detachably securing the thrust ring to the base so that 15 upon release of said detachable securing means the table, supporting bearing and upthrust bearing assembly may be withdrawn from the base as a unit.

3. In a rotary well drilling machine, the combination of a base having an upstanding annular wall, a gear table, a gear table supporting bearing assembly, means for rotatably supporting the gear table supporting bearing assembly on a shoulder formed within the enclosure of the base, an upthrust bearing assembly, the gear table having a downwardly extending annular element extending downwardly into the base, means for detachably and adjustably supporting the up-
thrust bearing on the said annular element, a 20 thrust ring interposed between the supporting and upthrust bearings, and means for detachably securing the thrust ring to the base so that on release of the detachable means the rotary table, including the said bearing assemblies, may 25 be withdrawn from the base as a unit.

4. In a rotary machine, the combination of a base having an opening therethrough and provided with an upstanding annular wall, a gear table mounted on the base and having an annular 40 skirt extending into said opening, the periphery of the gear table extending over the edge of the upstanding wall of the base to provide a seal between the base and the gear table to resist the entrance of foreign matter into the base, a gear 45 table supporting bearing mounted on the base, an upthrust bearing including a ring having a downwardly extending annular groove and mounted upon the skirt of the table within the base between the base and the gear table, the base being 50 provided near the lower end of the skirt of the table with an integrally formed upstanding annular wall adapted to cooperate with the downwardly extending annular groove in the bearing ring to prevent the admission of foreign matter 55 to within the interior of the base from the underside of the table.

5. In a rotary machine, the combination of a base having an upstanding annular wall, a gear table mounted within the base and having its 60 periphery cooperating with the upstanding wall to define a seal against the entrance of foreign matter into the base enclosure, bearing means for rotatably supporting the table on the base, gear means for driving the rotary table relative to the base, a shaft having a pinion to drive the gear means, bearings for the shaft, means defining a lubricant chamber for the shaft bearings, means defining a separate lubricant chamber for the 65 pinion and gear means, means providing a separate lubricant chamber for the gear table bearing means, separate lubricant openings in the base for supplying lubricant to each of said chambers, and passages formed in the base for separately 70 75

- conducting lubricant from the said openings to the separate chambers.
6. In a rotary machine, the combination of a base having an upstanding outer annular wall, a rotary table having a gear positioned within said annular wall, a pinion shaft, a pinion carried by said shaft to mesh with and drive the gear of the rotary table, a second upstanding wall formed on the base inwardly concentric from the outer annular wall, bearing means for the rotary table supported by the base, means for supplying lubricant to the bearings, means for supplying lubricant to the pinion and gear of the rotary table, a third concentric upstanding wall carried by the base intermediately of said first and second annular walls, a flange on the table overlapping a portion of the outer periphery of said third wall to provide a labyrinth restriction between said wall and flange.
10. In a rotary machine, the combination of a base, a gear table rotatably supported by the base, bearing means for supporting the gear table on the base, gear means for driving the gear table, means cooperating with said base and table to define an enclosure for said gear means, means for supplying lubricant for the bearing means, means for supplying lubricant for the gear means, an upstanding annular partition carried by the base to separate the lubricants provided for the bearing means and the gear means, and a downwardly extending flange carried by said table to overlap a portion of the outer periphery of said annular partition to provide a labyrinth restriction between said flange and partition.
15. In a rotary machine, the combination of a base, a gear table rotatably supported by the base, gear means for driving the table, means providing a lubricant sump for lubricant for the gear means, and means providing an overflow for fluid within the sump to overflow excess fluid from the lower portion of said sump.
20. In a rotary machine, the combination of a base, a gear table rotatably supported by the base, gear means for driving the table, means providing a lubricant sump for lubricant for the gear means, means providing an overflow for fluid within the sump to overflow excess fluid from the lower portion of said sump, and means mounted within the sump for forcibly cleaning the sump through the overflow.
25. In a rotary machine, the combination of a base, a gear table rotatably supported by the base, the base having an outer annular wall formed to provide a channel, the table being formed to provide an annular lip extending into the channel, and means for forming a grease seal in the channel between the lip and the walls of the channel.
30. In a rotary machine, the combination of a base, a gear table rotatably supported by the base, the base having an upwardly extending outer annular wall, means providing an annular lip and channel seal between the table and the outer annular wall, and openings formed in the base structure for draining foreign matter thrown by the table through the structure of the base.
35. In a rotary machine, the combination of a base having an opening therein, a table rotatably supported by the base, bearing means for rotatably supporting the table on the base, upthrust bearing means for rotatably supporting the table within the base against upward thrust, the upthrust bearing means including a bearing supporting ring, a downwardly extending skirt formed on the rotary table to which the bearing
- supporting ring is adjustably secured, the ring and supporting bearing being removable upwardly through the opening in the base upon removal of the table, and cooperating flange means formed between the bearing supporting ring and the base on the underside of the supporting ring for excluding foreign matter from the upthrust bearings, said flange means on the base being formed integrally therewith.
40. In a rotary machine, the combination of a base, a rotary table rotatably supported by the base, the base having an upwardly extending annular wall, cooperating means between the upstanding wall and the table forming a labyrinth path to resist the entrance of foreign matter into the interior of the annular wall of the base, a guard ring secured to the base to extend inwardly over the rotary table, a foreign matter draining passage formed in the downwardly extending flange of the table guard, and the guard being formed to provide a flange to cooperate with a groove in the rotary table to resist the passage of foreign matter to the joint between the table and the upstanding wall.
45. In a rotary machine for drilling wells, the combination of a base having an upstanding annular wall, a gear table mounted within the annular wall, including a downwardly extending annular member, cooperating means between the upstanding wall and the table to define a labyrinth path to resist the entrance of foreign matter into the interior of the annular wall of the base, means providing an annular supporting shoulder within the base, a bearing thrust ring mounted upon the shoulder, a supporting bearing mounted upon the thrust ring to rotatably support the table, an upthrust bearing assembly operatively engaging the thrust ring, means for adjustably securing an element of the upthrust bearing assembly to the downwardly extending annular member of the table to enable relative adjustment of the upthrust and supporting bearings between the table and the thrust ring, and means accessible from the under side of the base for detachably securing the thrust ring to the base so that upon release of said detachable securing means the table and supporting and upthrust bearing assemblies may be withdrawn from the base as a unit.
50. In a rotary machine for drilling wells, the combination of a base having an upstanding annular wall, a gear table mounted within the annular wall, including a downwardly extending annular member, cooperating means between the upstanding wall and the table to define a labyrinth path to resist the entrance of foreign matter into the interior of the annular wall of the base, means providing an annular supporting shoulder within the base, a bearing thrust ring mounted upon the shoulder, a supporting bearing mounted upon the thrust ring to rotatably support the table, said bearing thrust ring having inner and outer upstanding walls to define a lubricant chamber for the supporting bearing, an upthrust bearing assembly operatively engaging the thrust ring, means for adjustably securing an element of the upthrust bearing assembly to the downwardly extending annular member of the table to enable relative adjustment of the upthrust and supporting bearings between the table and the thrust ring, and means accessible from the underside of the base for detachably securing the thrust ring to the base so that upon release of said detachable securing means the table, supporting and upthrust bearing assemblies may be withdrawn from the base as a unit.
55. In a rotary machine for drilling wells, the combination of a base having an upstanding annular wall, a gear table mounted within the annular wall, including a downwardly extending annular member, cooperating means between the upstanding wall and the table to define a labyrinth path to resist the entrance of foreign matter into the interior of the annular wall of the base, means providing an annular supporting shoulder within the base, a bearing thrust ring mounted upon the shoulder, a supporting bearing mounted upon the thrust ring to rotatably support the table, said bearing thrust ring having inner and outer upstanding walls to define a lubricant chamber for the supporting bearing, an upthrust bearing assembly operatively engaging the thrust ring, means for adjustably securing an element of the upthrust bearing assembly to the downwardly extending annular member of the table to enable relative adjustment of the upthrust and supporting bearings between the table and the thrust ring, and means accessible from the underside of the base for detachably securing the thrust ring to the base so that upon release of said detachable securing means the table, supporting and upthrust bearing assemblies may be withdrawn from the base as a unit.
60. In a rotary machine for drilling wells, the combination of a base having an upstanding annular wall, a gear table mounted within the annular wall, including a downwardly extending annular member, cooperating means between the upstanding wall and the table to define a labyrinth path to resist the entrance of foreign matter into the interior of the annular wall of the base, means providing an annular supporting shoulder within the base, a bearing thrust ring mounted upon the shoulder, a supporting bearing mounted upon the thrust ring to rotatably support the table, said bearing thrust ring having inner and outer upstanding walls to define a lubricant chamber for the supporting bearing, an upthrust bearing assembly operatively engaging the thrust ring, means for adjustably securing an element of the upthrust bearing assembly to the downwardly extending annular member of the table to enable relative adjustment of the upthrust and supporting bearings between the table and the thrust ring, and means accessible from the underside of the base for detachably securing the thrust ring to the base so that upon release of said detachable securing means the table, supporting and upthrust bearing assemblies may be withdrawn from the base as a unit.
65. In a rotary machine for drilling wells, the combination of a base having an upstanding annular wall, a gear table mounted within the annular wall, including a downwardly extending annular member, cooperating means between the upstanding wall and the table to define a labyrinth path to resist the entrance of foreign matter into the interior of the annular wall of the base, means providing an annular supporting shoulder within the base, a bearing thrust ring mounted upon the shoulder, a supporting bearing mounted upon the thrust ring to rotatably support the table, said bearing thrust ring having inner and outer upstanding walls to define a lubricant chamber for the supporting bearing, an upthrust bearing assembly operatively engaging the thrust ring, means for adjustably securing an element of the upthrust bearing assembly to the downwardly extending annular member of the table to enable relative adjustment of the upthrust and supporting bearings between the table and the thrust ring, and means accessible from the underside of the base for detachably securing the thrust ring to the base so that upon release of said detachable securing means the table, supporting and upthrust bearing assemblies may be withdrawn from the base as a unit.
70. In a rotary machine for drilling wells, the combination of a base having an upstanding annular wall, a gear table mounted within the annular wall, including a downwardly extending annular member, cooperating means between the upstanding wall and the table to define a labyrinth path to resist the entrance of foreign matter into the interior of the annular wall of the base, means providing an annular supporting shoulder within the base, a bearing thrust ring mounted upon the shoulder, a supporting bearing mounted upon the thrust ring to rotatably support the table, said bearing thrust ring having inner and outer upstanding walls to define a lubricant chamber for the supporting bearing, an upthrust bearing assembly operatively engaging the thrust ring, means for adjustably securing an element of the upthrust bearing assembly to the downwardly extending annular member of the table to enable relative adjustment of the upthrust and supporting bearings between the table and the thrust ring, and means accessible from the underside of the base for detachably securing the thrust ring to the base so that upon release of said detachable securing means the table, supporting and upthrust bearing assemblies may be withdrawn from the base as a unit.
75. In a rotary machine for drilling wells, the combination of a base having an upstanding annular wall, a gear table mounted within the annular wall, including a downwardly extending annular member, cooperating means between the upstanding wall and the table to define a labyrinth path to resist the entrance of foreign matter into the interior of the annular wall of the base, means providing an annular supporting shoulder within the base, a bearing thrust ring mounted upon the shoulder, a supporting bearing mounted upon the thrust ring to rotatably support the table, said bearing thrust ring having inner and outer upstanding walls to define a lubricant chamber for the supporting bearing, an upthrust bearing assembly operatively engaging the thrust ring, means for adjustably securing an element of the upthrust bearing assembly to the downwardly extending annular member of the table to enable relative adjustment of the upthrust and supporting bearings between the table and the thrust ring, and means accessible from the underside of the base for detachably securing the thrust ring to the base so that upon release of said detachable securing means the table, supporting and upthrust bearing assemblies may be withdrawn from the base as a unit.

16. In a rotary well drilling machine, the combination of a base, a table rotatably supported by the base, bearing means for rotatably supporting the table on the base, upthrust bearing means for rotatably supporting the table within the base against upward thrust, said upthrust bearing means being positioned below the plane of said table supporting bearing means, the upthrust bearing means including a bearing supporting ring, a downwardly extending skirt formed on the rotary table to which the bearing supporting ring is adjustably secured, and an inwardly projecting wall formed integrally with said base below the bearing supporting ring to prevent direct impingement of any foreign matter upwardly between the outer periphery of the bearing ring and the surrounding adjacent wall of the base. 5
17. In a rotary machine, the combination of a base, a rotary table having a gear and being rotatably supported by the base, the base having an upwardly extending outer annular wall, means providing an annular lip and groove seal between the table and the outer annular wall, an inner annular wall spaced from the outer wall and enclosing said table gear to provide a lubricant chamber, and means providing an annular lip and groove seal between the table and the inner annular wall, the passage defined between the inner and outer walls communicating with the opening in the bottom of the base to drain any foreign matter which passes the lip and groove seal between the outer wall and the table. 10
18. In a rotary machine, a base including a pair of spaced longitudinal sills formed integral with the base, a spider supporting flange formed in the base, and cross-beams formed integrally with the base on opposite sides of the opening in the flange, said cross-beams having a web section flush with the bottom face of the sills to provide a support around the flange opening. 15
19. In a rotary machine, the combination including a base having an outer upstanding wall and an inner upstanding wall providing a lubricant reservoir, an overflow passage formed in the base to define the maximum level of lubricant within the chamber, said passage extending to a point near the bottom of the reservoir so that foreign matter including water on settling to the bottom of said chamber would be discharged through the overflow passage on admission of further lubricant to said reservoir. 20
20. In a rotary machine, the combination including a base having an outer upstanding wall and an inner upstanding wall providing a lubricant reservoir, an overflow passage formed in the base to define the maximum level of lubricant within the chamber, said passage extending to a point near the bottom of the reservoir so that foreign matter including water on settling to the bottom of said chamber would be discharged through the overflow passage on admission of further lubricant to said reservoir, and means mounted in the reservoir and acting through the overflow passage for forcibly discharging fluid from said reservoir. 25
21. In a rotary machine, the combination including a base including spaced longitudinal sills formed integrally with the base, the base having a vertically extending opening, a spider supporting flange formed in the base opening near the lower end thereof, and cross-beams formed integrally with the base on opposite sides of the opening to provide a support around the flange opening. 30
22. In a rotary machine, the combination including a base having an outer annular wall and including a pinion shaft supporting portion extending outwardly from the annular wall, a rotary table rotatably supported by the base within the annular wall, and the pinion shaft supporting portion being provided with an integrally formed flat upper surface which is substantially flush with the surface of the rotary table. 35
23. In a rotary machine, the combination of a base having a vertical opening therethrough and an outer annular flange, a rotary table mounted in the opening within the outer annular flange, the base being provided with an outwardly extending portion formed integrally with the base of substantially rectangular cross section, the upper surface of which portion is flat and lies substantially in the plane of the surface of the table. 40
24. In a rotary machine, the combination of a base having an upwardly extending annular wall, a rotary table rotatably supported within an opening formed in the base, the rotary table being formed to provide a labyrinth path at the upper edge of the wall, a guard ring supported by the base and including an annular section adapted to extend horizontally over the surface of the rotary table, and a horizontal section adapted to cooperate with an annular groove formed in the edge of the rotary table, and vertically extending annular sections cooperating with the said horizontal sections to guide mud or other fluids from the surface of the rotary table to the exterior of the annular wall of the base. 45
25. In a rotary machine, the combination of a base having an upwardly extending annular wall, a rotary table rotatably supported within an opening formed in the base, the rotary table being formed to provide a labyrinth path at the upper edge of the wall, a guard ring supported by the base and including an annular section adapted to extend horizontally over the surface of the table in spaced relation thereto to provide a channel through which mud or other fluids are thrown from the surface of the rotary table as the rotary table revolves and which guard ring includes a vertically extending passage for the receipt of said mud or other fluid to guide the same to the exterior of the wall of the base of the rotary machine, and which guard ring includes an intermediate section extending horizontally to 50 cooperate with a sealing groove formed in the periphery of the rotary table. 55
26. In a rotary machine, the combination of a base having an upwardly extending annular wall, a rotary table rotatably supported within an opening formed in the base, the rotary table being formed to provide a labyrinth path at the upper edge of the wall, a guard ring supported by the base and including an annular section adapted to extend horizontally over the surface of the table in spaced relation thereto to provide a channel through which mud or other fluids are thrown from the surface of the rotary table as the rotary table revolves and which guard ring includes a vertically extending passage for the receipt of said mud or other fluid to guide the same to the exterior of the wall of the base of the rotary machine, and which guard ring includes an intermediate section extending horizontally to 60 cooperate with a sealing groove formed in the periphery of the rotary table, and said guard ring including a second vertically extending section spaced from the edge of the rotary table and from the annular wall of the base to provide a second 65
- 70
- 75

- passage for mud or other fluid to pass down the exterior of the annular wall of the base.
27. In a rotary well drilling machine, the combination of a base having an upstanding annular wall, a gear table, a gear table supporting bearing assembly, means for rotatably supporting the gear table supporting bearing assembly on a shoulder formed within the base, an upthrust bearing assembly, the gear table having a downwardly extending element extending downwardly into the base, means for securing the upthrust bearing on said annular element, a thrust ring interposed between the supporting and upthrust bearings, means for detachably securing the thrust ring to the base so that on release of the detachable means the rotary table, including the bearing assemblies, may be withdrawn from the base as a unit, and means mounted within the base and adapted to cooperate with the thrust ring to orient the assembly of the rotary table and bearing assemblies with relation to the base so as to prevent relative rotary movement of the thrust ring and base and to permit the detachable securing means to be actuated to secure the said assembly of the rotary table and bearing assemblies to the base.
28. In a rotary machine, the combination of a base having an annular wall and including a pinion shaft supporting portion extending outwardly from the annular wall, a gear table rotatably supported by the base within the annular wall, cooperating means between the annular wall and the table forming a labyrinth path to resist the entrance of foreign matter into the enclosure defined between the wall and the gear table, said pinion shaft supporting portion being provided with an integrally formed flat upper surface which is parallel to the upper surface of the gear table, means defining a drainage channel between the annular wall of the base and the pinion shaft supporting portion of the base, said channel communicating with the opening in the bottom of the base to drain any foreign matter entering said channel from the top portion of the rotary machine.
29. In a rotary machine, the combination of a base having an annular wall and including a pinion shaft supporting portion extending outwardly from the annular wall, a gear table rotatably supported by the base within the annular wall, cooperating means between the annular wall and the table forming a labyrinth path to resist the entrance of foreign matter into the enclosure defined between the wall and the gear table, said pinion shaft supporting portion being provided with an integrally formed flat upper surface which is parallel to the upper surface of the gear table, said upper surface having an extension which conforms closely to the periphery of the gear table, a drainage passage communicating with the opening in the bottom of the base to drain any foreign matter passing between said extension and the periphery of the gear table and entering said passage.
30. In a rotary well drilling machine, including a base having a central opening, a rotary table having a bore defined by an extension projecting through the central opening of the base, a spider positioned in the table bore and adapted to be either locked to the base or to the table, the locking to the base or the table being accomplished solely by movement of the spider, the combination of a supporting bearing on said base encircling the extension of the table for rotatably supporting the table, and an upthrust bear-

ing between the table and the base carried by the extension formed on said table.

31. In a rotary well drilling machine, including a base having a central opening, a rotary table having a bore defined by an extension projecting into the central opening, a spider positioned in the bore and having a single set of lugs, said lugs being adapted to be engaged either with the table or with the base, the engaging of the lugs with the base or table being accomplished solely by movement of the spider, the combination of a supporting bearing on said base encircling the extension of the table for rotatably supporting the table, and an upthrust bearing between the table and the base carried by the extension formed on the table, said upthrust bearing being positioned below the plane of said supporting bearing. 5

32. In a rotary well drilling machine, including a base having a central opening, a rotary table having a bore defined by an extension projecting into the central opening, a set of diametrically opposed pockets formed in the base, a set of diametrically opposed pockets formed in the bore, a spider mounted in the bore and having a set 25 of diametrically opposed lugs formed on the spider and adapted to be engaged with either the pockets in the table or the base, the engaging of said lugs with the table or the base being accomplished solely by movement of said spider, 30 the combination of a supporting bearing on said base encircling the extension of the table for rotatably supporting the table, and an upthrust bearing between the table and the base carried by the extension formed on said table, said upthrust bearing being positioned below the plane 35 of said supporting bearing.

33. In a rotary well drilling machine, including a base having a central opening, a rotary table having a bore defined by an extension projecting into the central opening, a plurality of spaced pockets formed in the bore of the said table, a plurality of equally spaced pockets formed in the base, a spider mounted in the bore and having a plurality of lugs spaced on its periphery so as to correspond to the spacing of said pockets, the said lugs being adapted to be engaged with either the pockets in the table or base, said engagement of the lugs with either the said table or base pockets being accomplished solely by movement of said spider, the combination of a supporting bearing on said base encircling the extension of the table for rotatably supporting the table, and an upthrust bearing between the table and the base carried by the extension formed on said table, said upthrust bearing being positioned below the plane 45 of said supporting bearing. 50

34. In a rotary well drilling machine, including a base having a central opening, a rotary table having a bore defined by an extension projecting into the central opening, a plurality of spaced pockets formed in the bore of said table spaced to provide passages, a plurality of equally spaced pockets formed in the base, a spider 60 mounted in the said bore and having a plurality of lugs spaced on its periphery so as to correspond with the spacing of said pockets, the said lugs being adapted to be engaged with either the pockets in the table or base, said engagement of the lugs with either the said table or base pockets being accomplished solely by movement of said spider, the said lugs being adapted to pass through the passage formed between the pockets 65 formed in the bore of said table, the combina- 70

75

tion of a supporting bearing on said base encircling the extension of the table for rotatably supporting the table, and an upthrust bearing between the table and the base carried by the extension formed on said table, said upthrust bearing being positioned below the plane of said supporting bearing.

35. In a rotary well drilling machine, including a base having a central opening, a rotary table having a bore defined by an extension projecting into the central opening, a plurality of spaced segmental lugs formed in the bore of the table and providing spaced pockets in the bore of the table, a plurality of equally spaced pockets formed in the base, a spider mounted in the said bore and having a plurality of lugs spaced on its periphery so as to correspond with the spacing of the said pockets, the said lugs being adapted to be engaged with either the pockets in the table or the base, said engagement of the lugs with either the table or base pockets being accomplished solely by vertical movement and rotation of the said spider, the combination of a

supporting bearing on said base encircling the extension of the table for rotatably supporting the table, and an upthrust bearing between the table and the base carried by the extension formed on said table said upthrust bearing being positioned below the plane of said supporting bearing.

36. In a rotary well drilling machine, including a base having a central opening, a rotary table having a bore defined by an extension projecting into the central opening, a spider positioned in the table bore and adapted to be insertable and removable from the top of the table, and means formed integrally with said base and adapted to nonrotatably support said spider on the base, the combination of a supporting bearing on said base encircling the extension of the table for rotatably supporting the table, and an upthrust bearing between the table and the base carried by the extension formed on said table, said upthrust bearing being positioned below the plane of said supporting bearing.

JOHN D. SPALDING.
